SEPARABLE FASTENER

Eberhard H. Dau, Ingram, Pittsburgh, Pa.

Application October 10, 1935, Serial No. 44,349

4 Claims. (Cl. 24—205)

This invention relates to separable fasteners, and particularly to those which are composed of a plurality of interlocking members that are attached to a pair of flexible stringers or tapes, and operated by a suitable slide device.

Separable interlocking fasteners of this type have become extremely popular for a variety of uses, and are made in a number of ways. At first, the fastener elements were formed of sheet metal and clamped by integral leg portions to the stringer, or tape member, which was provided with a reenforced receiving or attaching edge. Subsequently, the fastener elements have been formed by die casting, and in some instances 10 of material other than metal; such as various types of plastics which lend themselves readily to molding. Such non-metallic fastener elements may be colored to increase their sales appeal, and do not conduct heat as readily as those 15 formed of metal. In addition, they are lighter in weight, and cheaper to manufacture.

It is one of the objects of the present invention to provide a novel separable fastener having not only the advantages of those of the prior art but 20 also one in which the interlocking fastener elements are attached to their stringer or tape members solely by adhesion at their bases, whereby by the heretofore necessary leg portions are eliminated. By this method of attachment, it is 25 practical to make a separable fastener in which the greatest thickness of the assembled device is the thickness of the stringer, or tape. This last named feature is very important and desirable 30 due to the fact that the fastener elements per se may be spaced inwardly from the sides of the reenforced edge of the stringer, or tape, and the operating slide device moved in contact along the latter, thus enabling a smoother operation. In 35 addition, the inward spacing of the sides of the interlocking fastener elements with respect to the sides of the reenforced edge of the stringer, or tape, permits the latter to serve as the sole area of contact with the object to be enclosed by the device to which the assembled fastener is 40 applied; for instance, the body of a person wearing an undergarment employing the separable fastener of the invention.

The foregoing and further objects will be apparent after referring to the drawings, in which: 45 Figure 1 is an end elevation of a stringer, or tape, with a fastener element of the invention attached thereto.

Figure 2 is a fragmentary plan disclosing a 50 pair of stringers, or tapes, with a series of the fastener elements in interlocked relation.

Figure 3 is a fragmentary perspective of one of the stringers, or tapes, of Figure 2.

Figure 4 is a sectional end elevation of a form of apparatus which may be employed to manufacture the device of the invention.

Figure 5 is a view similar to Figure 4 but disclosing some of the elements of the apparatus in other operative positions.

Figure 6 is a fragmentary side elevation illustrating the manner in which the stringer, or tape, and its attached fastener elements are removed from a portion of the apparatus of Figures 4 and 5.

Referring more particularly to the drawings, the numeral 2 designates a stringer, or tape, 15 which preferably has one of its edges reenforced in a suitable manner, as shown at 3. Both the stringer and its reenforced edge are preferably formed of fabric or other suitable material which is not only flexible but relatively absorbent.

According to the teaching of the invention, the novel fastener elements per se are formed of a suitable moldable material, which may be any of a number of plastic substances, and are attached to the reenforced edge 3 of the stringer, or tape, 20 2 solely by adhesion. That is to say, they are attached without the use of the usual integral leg portions which tightly embrace the stringer. It will, of course, be readily understood by those 25 skilled in the art that if the stringer, or tape, 2 30 is of sufficient thickness the reenforced edge 3 may, if desired, be dispensed with.

The numeral 4 generally designates the fastener elements which are so treated as to be rendered plastic and partially absorbed by the 35 reenforced edge 3 of the stringer 2. The absorbed portion of one of the fastener elements 4 is illustrated at 5 in Figures 1 and 3. Thus, the fastener elements are secured to the stringer 2 without employing the usual integral legs, or other 40 embracing portions, as is the case in conventional practice.

By adhering the fastener elements 4 in this manner, the overall thickness of the assembled fastener of the invention may be represented by 45 the thickness of the reenforced edge 3 of the stringer 2. In other words, the thickness of the reenforced edge 3, as indicated at A, may be at least as great, or greater, than the width B of the fastener elements 4; whereby the numerous advantages previously referred to are obtained.

As shown in Figure 3 of the drawings, the fastener elements 4 are substantially V-shaped in cross-section and concavo-convex longitudinally of their axes (the convexities being represented 50 55

at 6 and the concavities at 10. The wing portions of the substantially V-shaped fastener elements are shown as being substantially semi-cylindrical on their transverse axes. For the purpose of greater tenacity, or adherence, the bases of the wings of the V-shaped fastener elements 4 are preferably thicker than the outer ends thereof.

According to the foregoing, it will be noted that the fastener elements 4 are distinct from the stringers 2 and defined by surfaces other than the surfaces of the stringers; and also that the surfaces defining the fastener elements 4 are extended beyond the surfaces of those portions of the stringers by which they are carried. In other words, the stringers form no part of the interlocking surfaces of the fastener elements.

Referring to Figures 4, 5 and 6, I have illustrated one form of apparatus which may be used to make the article of my invention. According to this form of apparatus, the numeral 9 designates a pair of cooperating mold elements whose most adjacent surfaces are shown at 10. These surfaces 10 of the mold elements 9 are connected to slightly inwardly spaced mold surfaces 12 by recesses 13. The upper ends of the adjacent sides of the mold elements 9 are further inwardly spaced, as at 14, to receive an element to be later described.

Each of the mold elements 9 is provided with a longitudinal aperture 16 in which there is disposed a suitable heating medium, such as electrical resistance heating elements 17, which are thermostatically controlled.

A vertically movable carrier-head 19 is adapted for reciprocation within the recess provided by the inwardly spaced surfaces 14 on the adjacent sides of the mold elements 9. This carrier-head 19 carries a pair of die plungers 20 which are secured thereto in any suitable manner and extended downwardly therefrom and shaped to provide a plurality of male die elements 21. These male die elements 21 are of such shape as will form the fastener elements 4 from a suitable plastic substance.

In operation, a stringer, or tape, 2 is disposed between the most adjacent surfaces 10 of the mold elements 9 with its reenforced edge occupying the recesses 13. The mold elements 9 are held in adjacency (the degree of which may, if necessary, be carefully regulated), by any suitable means. While the mold elements 9 are in this position, a suitable plastic or moldable substance 22 (in any convenient form) is disposed between the slightly inwardly spaced mold surfaces 12 and on the top of the reenforced edge 3 of the stringer 2. This plastic substance 22 may, as shown, be in the form of a rectangular stick of compacted particles of a suitable plastic substance; or in any other character or shape.

The mold elements 9 having previously been brought to the required and controlled temperature, will immediately tend to render plastic the moldable substance 22. The carrier-head 19 is then lowered into the recess provided by the inwardly spaced surfaces 14 of the mold elements 9, and the die elements 21 are brought into contact with the substance 22, which is shaped thereby. Preferably, the die elements 21 are maintained at substantially the same temperature as that of the die elements 9 by any suitable means. This means may, of course, be other than the resistance heating elements 17.

The heat and pressure developed by the joint effects of the mold elements 9 and die elements 21 shape the plastic or moldable substance 22 into the form of the fastener elements 4 and simultaneously cause portions 5 of the latter to be absorbed by the reenforced edge 3 of the tape 2, whereby adherence is effected.

After a sufficient interval of time has elapsed (to effect "curing"), the mold elements 9 are separated and the tape 2 pulled away from the die elements 21 in the manner shown in Figure 6.

The mold elements 9, die plungers 20, etc. may be of any length desired, whereby the separable interlocking fasteners of the invention can be produced in extreme lengths.

While I have shown and described one specific embodiment of my invention, it will be understood that I do not wish to be limited exactly thereto, since various modifications may be made without departing from the scope of my invention, as defined by the following claims.

I claim:

1. A separable fastener comprising a pair of stringers carrying a plurality of opposed interlocking fastener members which are constructed and arranged to interlock with their longitudinal axes occupying a common plane, said opposed interlocking fastener members being distinct from said stringers and defined by surfaces other than the surfaces of said stringers, the surfaces defining said interlocking fastener members being extended beyond the surfaces of those portions of said stringers by which they are carried, the thickness of the edges of said stringers being at least equal to the width of the bases of the interlocking fastener members carried thereby.

2. A separable fastener comprising a pair of stringers, each of said stringers being provided with a reenforced edge carrying a plurality of opposed interlocking fastener members which are constructed and arranged to interlock with their longitudinal axes occupying a common plane, said opposed interlocking fastener members being distinct from said stringers and defined by surfaces other than the surfaces of said stringers, the surfaces defining said interlocking fastener members being extended beyond the surfaces of those portions of said stringers by which they are carried, the thickness of the reenforced edges of said stringers being at least equal to the width of the bases of the interlocking fastener members carried thereby.

3. A separable fastener comprising a pair of stringers carrying a plurality of opposed interlocking fastener members, said interlocking fastener members being substantially V-shaped in cross-section and concavo-convex longitudinally over their axes, the entireties of the wings formed by said V-shaped interlocking fastener members being tapered longitudinally toward the opposing interlocking fastener members.

4. A separable fastener comprising a pair of stringers carrying a plurality of opposed interlocking fastener members, said interlocking fastener members being substantially V-shaped in cross-section and concavo-convex longitudinally over their axes, the shape of each of the wings formed by said V-shaped interlocking fastener members in a transverse plane being substantially that of a segment of a cylinder.
